UNITED STATES PATENT OFFICE.

NORBERT M. LA PORTE, OF BALTIMORE, MARYLAND, ASSIGNOR TO THE CROWN CORK AND SEAL COMPANY OF BALTIMORE CITY, OF BALTIMORE, MARYLAND, A CORPORATION OF MARYLAND.

CAPPING-MACHINE.

1,123,559.

Specification of Letters Patent.

Patented Jan. 5, 1915.

Application filed February 2, 1911. Serial No. 606,096.

To all whom it may concern:

Be it known that I, NORBERT M. LA PORTE, a citizen of the United States, residing at Baltimore, State of Maryland, have invented certain new and useful Improvements in Capping-Machines, fully described and represented in the following specification and the accompanying drawings, forming a part of the same.

20 This invention relates to improvements in capping machines, that is, machines for applying metal caps to receptacles for the purpose of closing the same.

One of the objects of the invention is to 25 produce an improved capping machine in which bottles of varying heights and capacities may be rapidly and accurately presented to the cap applying mechanism, so as to have the caps applied thereto.

With this and other objects not specifically referred to in view, the invention consists in certain constructions, and in certain parts, improvements and combinations as 30 will be hereinafter fully described and then 25 specifically pointed out.

Referring to the accompanying drawings—Figure 1 is a side elevation of a machine constructed in accordance with the invention. Fig. 2 is a front view of the 35 bottle holder and cap applying head of the machine shown in Fig. 2. Fig. 3 is a sectional view on the line 3—3 of Fig. 1. Fig. 4 is a sectional view on the line 4—4 of Fig. 2. Fig. 5 is a vertical sectional view 40 taken through the cap applying head. Fig. 6 is a detail bottom plan view of the bottle holding means.

Referring to the accompanying drawings which illustrate one embodiment of 45 the invention, 1 indicates a base having an upright or column 2 thereon. This column, if desired, may be cast integral with the base.

Machines embodying the invention will 50 be provided with means for supporting the receptacles while being capped and with cap applying means. Such machines will also include means for producing a relative movement between the capping mechanism and the support, for the purpose of causing 55 the caps to be applied. In the particular machine illustrated, this relative movement is produced by mounting the capping head 3 on a reciprocating rod or post 4, the head 55 having an extension, as 5, provided with an

opening through which the upper end of the rod 4 passes, the two being secured together by a nut, as 6. The rod or post 4 passes through a hollow column or standard 7 which, in the particular construction shown, is cast in one piece with the standard 2. The lower end of this rod or post 4 is connected by a link 8 to a crank 9, indicated in dotted lines in Fig. 1, this crank being formed on the end of a crank-shaft 60 supported in suitable bearings in the base 1. The shaft is provided with a constantly driven fly-wheel 10 illustrated as driven by a belt 11 from an electric motor 12 mounted on a split bracket 13 supported on the 70 standard 2. A single revolution clutch 14, controlled by a treadle 14', is provided, by which the fly-wheel is clutched to and unclutched from the shaft. Driving mechanism of the character just described is well-known in the art and any other suitable 75 form of mechanism may be substituted therefor.

The cap applying mechanism may be varied as to its details of construction, but in 80 machines embodying the invention in its best form, it will be so constructed as to provide for minor inequalities in the heights of the receptacles to which the caps are to be applied. It is well-known that glass- 85 receptacles even though made in the same mold and intended to be counterparts, will vary somewhat in their vertical dimensions, and inasmuch as the capping mechanism has a constant stroke, there is danger of breaking 90 the receptacles unless some means is provided for taking care of these variations.

In the particular construction illustrated, the capping head is provided at its lower part with a hollow bending die 15 having 95 cap holding fingers 16, the die being supported in the capping head by a throat ring 17 threaded to the lower part of the capping head. This bending die is provided at the top with a shoulder 18 against which rests 100 a spring 19, the other end of the spring resting against a threaded adjusting block 20. In constructions embodying the invention, this spring 19 will be under an original predetermined compression. It will be 105 understood that the bending die shown and described is particularly adapted for bending in the flanges of metal caps of the well-known crown cork type. The original predetermined compression of the spring will 110

be so regulated that the flanges of crowns to be applied to the shortest bottles will be bent inward by the bending die without any substantial further compression of the spring. When, however, a longer bottle is presented thereto, the spring will yield sufficiently after the capping operation is effected so as to prevent the die from breaking the bottle. In the construction shown, a plunger 21 is provided, this plunger being backed up by a light spring 22. When a crown has been placed on the supporting fingers 16, the plunger 21 is forced back against its spring, and as the crown comes into position, the head 23 of the plunger 21 holds it against the fingers, thus preventing it from being displaced until it is fairly seated on the bottle mouth. The particular construction shown also includes a plunger 25 surrounded by a spring 26, the purpose of this plunger being to insure the positive discharge of the capped bottles, in case they do not readily clear themselves from the bending die after the caps have been applied.

While the bottle holding devices may be varied within wide limits, in machines which embody the invention in its best form, these bottle holding devices will be adapted to support a plurality of bottles of varying heights and capacities and to bring the different bottles into proper capping relation both vertically and axially with respect to the head. In the particular construction illustrated, the bottle holding means comprises a sleeve, as 30, this sleeve being provided with a plurality of arms 31. The particular machine illustrated is intended for capping bottles which hold a quart, a pint, and a half-pint respectively, and which, therefore, vary considerably in height. In order to bring the different bottles to be capped into proper relation vertically with respect to the capping head, the arms 31 are arranged at varying heights on the sleeve, as shown. Each of the arms, in the construction illustrated, is provided with a rest, as 32, these rests being secured to the arms 31 by bolts 33, or in any other suitable manner.

The bottle holder should, by its movement, bring the bottle to be capped not only into proper relation vertically with respect to the capping mechanism, but also should properly center it, that is to say, the vertical axis of the bottle to be capped should coincide with the vertical axis of the bending die in order to properly apply the cap to the bottle without danger of breakage. Constructions embodying the invention, therefore, will include suitable centering means which are rendered effective by the movement of the bottle holder. While these centering devices may be varied, in the particular construction illustrated, each of the rests

32 is provided with a centering member 34, these centering members 34 being arranged, as clearly shown in Fig. 3, at varying distances from the center of the support. As the sleeve 30 is rotated, it will bring the desired bottle into proper position with respect to the capping head, so that the caps may be applied thereto without any further adjustment. For instance, if the machine be employed in capping quart bottles, and it be desired to cap pints or half-pints, all that it is necessary to do in order to bring the desired bottle into proper capping relation both vertically and axially is to swing the sleeve around to bring the proper support under the capping head.

Means may be provided for locking the holder, and in the best constructions, these means will be provided. While the construction of the locking means may be varied, as shown the standard 7 is provided (see Fig. 4) with a pin 35, and the lower side of the sleeve is provided with a series of notches 36, the bottom of the sleeve being beveled off, as indicated at 37 on each side of the notch. The pin 35 is so located that as each of the arms 31 comes into proper position, the corresponding notch 36 will engage the pin 35 and hold the sleeve locked.

Changes and variations may be made in the construction by which the invention is carried into effect. The invention claimed, therefore, is not to be confined to the particular construction herein described and illustrated.

What is claimed is:—

1. In a capping machine, the combination with a capping head, of a bottle holder comprising a plurality of bottle supports having their supporting faces in different planes and being thereby adapted to support bottles of widely different sizes, said holder being movable beneath the head, so that a bottle thereon will be properly positioned both vertically and diametrically to be capped by the capping head, and means for effecting a relative capping movement between the holder and the head.

2. In a capping machine, the combination with a capping head, of a bottle holder comprising a plurality of bottle supports having their supporting faces in different planes and being thereby adapted to support bottles of widely different sizes, said holder being movable beneath the head, so that a bottle thereon will be properly positioned both vertically and diametrically to be capped by the capping head, means for effecting a relative capping movement between the holder and the head, and means for locking the holder in any of the positions to which it is moved.

3. In a capping machine, the combination with a capping head, of a bottle holder com-

- prising a plurality of bottle supports having their supporting faces in different planes and being thereby adapted to support bottles of widely different sizes, said holder being movable beneath the head, so that a bottle thereon will be properly positioned both vertically and diametrically to be capped by the capping head, means for effecting a relative capping movement between the holder and the head, and automatic means for locking the holder in any of the positions to which it is moved.
4. In a capping machine, the combination with a capping head, of a rotary bottle holder provided with a plurality of bottle supports arranged at different distances radially from the center of rotation of the holder and at different vertical heights, and a centering member for each support.
5. In a capping machine the combination with a capping head, of a rotary bottle holder provided with a plurality of bottle supports arranged at different distances radially from the center of rotation of the holder and at different vertical heights with respect to each other, a centering member for each support, and means for locking the holder in position with any support beneath the capping head.
6. In a capping machine the combination with a capping head, of a rotary bottle holder provided with a plurality of bottle supports arranged at different distances radially from the center of rotation of the holder and at different vertical heights with respect to each other, a centering member for each support, and means for automatically locking the holder in position with any support beneath the capping head.

In testimony whereof, I have hereunto set my hand, in the presence of two subscribing witnesses.

NORBERT M. LA PORTE.
